(57) **CLAIM**

The ornamental design for a sofa that converts into a lounger and a bed, as shown in FIGS. 1-12, and described herein.

DESCRIPTION

FIG. 1 is a front perspective view of the sofa that converts into a lounger and a bed, being in a sofa position;
FIG. 2 is a perspective view of the sofa that converts into a lounger and a bed, with a split backrest in which the left section of the split backrest is in a sofa position and the right section of the split backrest is in a bed position;
FIG. 3 is a perspective view of the sofa that converts into a lounger and a bed, being in a bed position;
FIG. 4 is a front view of the sofa that converts into a lounger and a bed, being in a sofa position;
FIG. 5 is a back view of the sofa that converts into a lounger and a bed, being in a sofa position;
FIG. 6 is a side view of the sofa that converts into a lounger and a bed, being in a sofa position;
FIG. 7 is a side view of the sofa that converts into a lounger and a bed, being in a sofa position;
FIG. 8 is a bottom view of the sofa that converts into a lounger and a bed, being in a sofa position;
FIG. 9 is a top view of the sofa that converts into a lounger and a bed, being in a sofa position;
FIG. 10 is a top view of the sofa that converts into a lounger and a bed, being in a bed position;
FIG. 11 is a perspective view of the sofa that converts into a lounger and a bed, being in a sofa position with raised arm sections; and,
FIG. 12 is a perspective view of the sofa that converts into a lounger and a bed, being in a lounge position.
The broken lines shown in the drawings are for illustrative purposes only and form no part of the claimed design.
